P. H. McCOOE.
ANTICREEPER FOR RAILWAY RAILS.
APPLICATION FILED JAN. 22, 1916.

1,215,392.

Patented Feb. 13, 1917.

Inventor:
Patrick H. McCoe.

By G. L. Clegg, Atty.

UNITED STATES PATENT OFFICE.

PATRICK H. MCCOOE, OF INDIANA HARBOR, INDIANA.

ANTICREEPER FOR RAILWAY-RAILS.

1,215,392.

Specification of Letters Patent. Patented Feb. 13, 1917.

Application filed January 22, 1916. Serial No. 73,541.

To all whom it may concern:

Be it known that I, PATRICK H. McCOOE, citizen of the United States, residing at Indiana Harbor, in the county of Lake and 5 State of Indiana, have invented a certain new and useful Improvement in Anticreepers for Railway-Rails, of which the following is a full, clear, concise, and exact description, reference being had to the accompanying 10 drawings, forming a part of this specification.

My invention relates to anticreepers for railway rails and in one of its aspects includes one clamping member having a portion for underlying the flange of a rail and terminating in upwardly projecting hooks and a second clamping member adapted to engage the rail flange and movable transversely of the rail along the first aforesaid 20 clamping member, these clamping members having interengagement for preventing the movement of the second mentioned clamping member transversely of the other member, or longitudinally of the track.

25 In accordance with another feature of my invention the inner upright faces of the aforesaid hooks in which one of the clamping members terminates slope one toward the other slightly. By this feature of the 30 invention the wedging block may better perform its function; it being received in the tapering spacing between the rail flange and an adjacent hook, the clamping member carrying such hook yielding sufficiently to enable the key to be driven into position substantially to fill the spacing.

I will explain my invention more fully by reference to the accompanying drawing showing the preferred embodiment thereof 40 and in which Figure 1 is a plan view illustrating a device of my invention in place; Fig. 2 is a sectional plan view on line 2-2 of Fig. 5; Fig. 3 is a perspective view illustrating parts of the structure; Fig. 4 is an- 45 other perspective view illustrating the device as applied to a rail; Fig. 5 is a sectional view on line 5-5 of Fig. 2; Fig. 6 is a horizontal section illustrating the sloping of one inner upright hook face with respect to the 50 opposing upright hook face.

Like parts are indicated by similar characters of reference throughout the different figures.

55 The track, of which one of the rails *a* is shown, is supported in any usual or preferred way upon ties, such a tie being indi-

cated at *b*. The rail illustrated is of the usual type employing a head and a base flange that are united by a vertical web. The clamp of my invention includes one 60 member whose intermediate portion *c* underlies the base flange *d* of the rail section *a* to which the device is applied, the portion *c* extending transversely of the rail (preferably at right angles thereto) and terminating at 65 its ends in hooks *e* and *f* which extend upwardly. The clamp member *c* has a tie abutting lug *c'* depending therefrom and 70 projecting beyond the same to engage the tie *b*. The hook *e* is shaped snugly to receive one side of the base flange, as illustrated in Fig. 4, but the hook *f* is enlarged to receive the complementary clamp member *g* which is desirably provided with upper and lower insetting lips *h*, *i* to form a channel 75 snugly receiving the contiguous side of the base flange. The top of the portion *c* leaves the bottom surface of the flange *d* where the lip *i* is disposed to afford space to receive such lip, as indicated in Fig. 3. The clamp member *g* has such interengagement with the complementary clamp member (preferably the portion *c* thereof) that it cannot be moved transversely of the other clamp member upon any creepage of the track rails. 80 This interengagement is desirably afforded by means of a tongue *k* which is received within a slot formed by and intervening between the lips *i* having substantially the same width as the tongue and desirably provided in the base of the clamping member *g*. 85 This slot divides the lip *i* into two parts between which the tongue *k* is received, both of these parts of this lip engaging the tongue whereby creepage of the clamping member *g* 90 longitudinally of the track and transversely of the complementary clamping member is prevented. Instead of constituting the clamping member *g* a wedge, I desirably make the upright part thereof that engages the edge of the rail flange *d* of uniform 95 thickness. I actuate the clamping member *g* by a wedging key *m* which is received within spacing that intervenes between the clamping member *g* and the upright part of the hook *f*. The key is driven into position 100 through this spacing, the inner face of the upright part of the hook *f* sloping slightly toward the opposed inner face of the upright part of the hook *e* whereby the channel way 105 that receives the key is tapered the better to enable said key to force the clamp member *g* 110

against the rail flange *d*. The portion *c* of the other clamping member will flex or bend sufficiently in the plane in which it lies to enable the key *m* to find its way through the 5 spacing between the clamping member *g* and the inner face of the upright portion of the hook *f*, the wing *m*¹ being thereafter bent over. The clamp member *g* is free to be moved by the key *m*, the tongue *k* having 10 only such engagement with the clamp member *g* as to prevent longitudinal movement of this clamp member with respect to the track while the two parts of the lip *i* have effective engagement only with the tongue *k* 15 for this same purpose.

When the device for preventing the creeping of the rail is in place spacing intervenes between the lug *c*¹ and the base of the rail and this lug projects beyond the main body 20 portion of the clamp member *c* into engagement with the tie *b*. If the rail moves or tends to move toward the tie the lug *c*¹ will turn or tend to turn the clamp in the plane of the rail base thereby increasing the grip 25 of the clamp upon the rail base to overcome the tendency to creep. If the rail should move or tend to move in the reverse direction the fixed relation of the clamp and rail would not be disturbed. By referring particularly to Figs. 1 and 5 it will be seen that 30 the top of the hook *f* overlies the channel formed between the lips *h* and *i* and therefore also overlies the part of the rail base that is received in this channel whereby the 35 top of the hook *f* holds the lip *h* from being warped out of position when the rail tends to rock or cant. By providing two lips that are spaced apart at their inner ends, the tongue *k* may be properly received there- 40 between without effectively interfering with the function of the lower jaw of the clamp member *g* that is formed by the separated lips *i*. The tongue *k* is also engaged with the bottom of the rail base. That is the 45 lower rail engaging side of the clamp member *g* is, for all practical purposes, as long and as effective as the upper side *h* of this clamp member. The tops of both hooks *e* and *f* are thus approached closely enough to

overlie the space that receives the base of 50 the rail.

While I have herein shown and particularly described the preferred embodiment of my invention I do not wish to be limited to the precise details of construction shown as 55 changes may readily be made without departing from the spirit of my invention, but having thus described my invention I claim as new and desire to secure by Letters Patent the following.

An anticerper for railway rails including one clamping member having a portion *c* for underlying the base of a rail and terminating in upwardly projecting hooks *e* and *f* whose tops overlie the space that receives 65 the base of a rail; a second clamping member *g* adapted to engage the base of the rail and movable transversely of the rail along the first clamping member, this second clamping member having the top lip *h* and 70 two separated bottom lips *i*, the clamp portion *c* being recessed to receive the lips *i* and having a tongue *k* passing into the space between the lips *i* to prevent the second clamping member *g* from moving longitudinally of the rail whose base is engaged by and between the lips *h* and *i* while resting upon the clamping portion *c*, the top of the hook *f* overlying the channel formed by the lips *h* and *i* and thereby overlying the base 75 of a rail that is received in this channel; a key *m* interposed between the upright portion of the hook *f* and the adjacent face of the clamping member *g* to force this clamping member into engagement with the base 80 of the rail; and a tie abutting lug depending from the clamp portion *c* and projecting beyond the same to afford a space between a tie engaged by said lug and the clamp portion *c*.

In witness whereof, I hereunto subscribe my name this seventeenth day of January 90
A. D., 1916.

PATRICK H. McCOOE.
